2,404,335

LIQUID FUEL BURNER, VAPORIZER, AND COMBUSTION ENGINE

Frank Whittle, Rugby, England, assignor to Power Jets (Research & Development) Limited, London, England

Application February 19, 1941, Serial No. 379,735
In Great Britain December 9, 1939

2 Claims. (Cl. 60—44)

1

This invention relates to liquid fuel burners and vaporizers and to combustion engines or systems employing the same. In particular, although not exclusively, it is applicable to power units of aircraft propulsion systems of the previously known or proposed type in which the output of an air compressor takes part in combustion and then drives a gas turbine which in turn drives the compressor, the effluent gases forming a propulsive reaction jet. The invention in some of its aspects is, however, applicable to liquid fuel burners and vaporizers used in quite different connections, for example, in water heating apparatus, steam raising boilers or otherwise, wherever a plurality of combustion chambers and burners are to be operated in parallel and it is especially desired to equalize the performance of all.

The primary object of the invention is to provide highly efficient and uniform fuel combustion and air heating by a plurality of burners in different combustion chambers. A further object is to provide a burner and vaporizer arrangement which will be effective in an airstream of extremely high velocity; another object is to improve on igniting arrangements where a plurality of burners are in separate combustion chambers, and yet another object is to provide structurally simple yet efficient liquid fuel supply, vaporizers, and burner arrangements in a power unit of the above mentioned type, wherein the compressor output is divided among a plurality of combustion chambers before being led into the turbine.

According to one feature of the invention, a plurality of fuel jets are supplied from a common source, in parallel, and in each individual connection a pressure-difference creating device such as a constriction, is provided, and is preferably so selected as to ensure the creation of a substantial pressure difference between the source and the jet in all ordinary running conditions. These constrictions are provided primarily to ensure that any disturbances of the resistance to flow occurring in one jet or associated vaporizer does not produce a surge of pressure or other inequality in a pipeline which is connected to another jet or jets and which may result in instability and fluctuation of fuel supply. According to another feature of the invention, each jet assembly preferably comprises a number of orifices arranged in spider or star fashion and directed substantially in an up-stream direction in a tubular combustion chamber through which an airstream of high velocity is created. Each jet is supplied by a vaporizer in the form of a pipe immediately

5 behind it in the airstream around which the combustion products pass. The combustion chamber surrounding the jets and vaporizers is preferably a tube which converges to the down-stream side of the jet and such tube is preferably co-axially surrounded by a duct which leads the air into the combustion chamber, the sense of direction of flow of the air being reversed as it passes from the outer to the inner passage. Preferably in the air-flow immediately before the jet, means are provided for establishing a high degree of turbulence in the air, and such means may take the form of concentric rings of vanes arranged with opposite or different pitch. Each combustion chamber may be provided with a pilot or starter jet for the purpose of providing the initial heat for the vaporizers, and each combustion chamber, or as is preferred, one chamber of a plurality, may be provided with igniting means comprising an electrical ignition plug. A feature of the invention resides in the interconnection of a plurality of combustion chambers by pipes for flame propagation as between one combustion chamber and its neighbor, and by this means only one chamber in a plurality need be equipped with igniting arrangements.

20 The invention as applied in a power unit as described in my co-pending application Serial No. 379,734, filed February 19, 1941, will now be described more fully with the aid of the accompanying drawings, in which:

25 Figure 1 is a sectional view of a combustion chamber and its ignition arrangements and fuel distributor, whilst

30 Figure 2 is an end view of the same, with the dome part removed, and

35 Fig. 3 is a diagrammatic view illustrating the interconnection of a plurality of combustion chambers.

40 For convenience, in Figure 1, the interconnecting stub pipes intended to be employed when a plurality of chambers are used in parallel are illustrated in rotationally displaced positions.

45 The combustion chamber is constituted by a cylindrical air casing 1, to which at one end is attached a dome end 2, and at the other end a suitable closure including a connection for compressed air supply, such as a dome 3 with a circular part 3A for the connection of an air trunk. 50 Within the casing 1 is mounted co-axially a flame tube 4 comprising a frusto-conical tube with a cylindrical portion 4A at its larger end. The smaller end of the flame tube 4, fits into an elbow part 5, which leads combustion products through 55 a right angle for exit through the wall of the cas-

ing 1. The casing 1, if it is one of a plurality required to operate in parallel (as in the power unit above mentioned), has air stub pipes 1A leading radially from it, to connect with neighboring casings. Within these air stubs 1A are substantially co-axially, flame stubs 4B similarly connecting the flame tube of one combustion chamber, to the flame tubes of its neighbors.

The dome 2 has passing through it a central, coaxial, bushing 2A into which fits a pilot jet 5, which is an atomising spray jet, supplied with fuel under pressure by a pipe 5A. The pilot jet projects practically into the flame region within the flame tube. Also into this region there projects the "live" electrode 6A of a spark plug 6 mounted in the dome 2, an "earth" electrode 6B being fitted to any convenient adjacent parts. Parts which would otherwise interfere with the electrode 6A are cut away to such clearance as is necessary to avoid sparks jumping in undesired places.

In the otherwise open end of the flame tube portion 4A, a baffle system is provided, the object of which is to produce a high degree of turbulence in air entering the flame tube at this end. This baffle system comprises a conical rim 7, an outer co-axial cylindrical sleeve 8, and an inner co-axial cylindrical sleeve 9. Between sleeves 8 and 9 is a series of swirl vanes 8A pitched one away—say, clockwise looking downstream, and between sleeve 9 and the bush 2A is an inner series of swirl vanes 9A, oppositely pitched. Air coming from the casing 1 flows through these two series of vanes as shown diagrammatically by the arrow 10, and the result is a highly turbulent, high velocity, flow of air in the flame region within the flame tube. Some reversal of flow in the neighborhood of the axis is to be found with this arrangement, and this appears to be beneficial in sustaining combustion.

Through the dome 2 and rim 7 there project eight fuel pipes 11, which continue substantially parallel with (and symmetrical about) the flame tube axis, for about half the length of the flame tube, and then bend back upon themselves to point upstream. They terminate in jets at 11A. The parts of these pipes which are exposed to the flame act as vaporizers, so that whilst liquid fuel is fed into the pipes 11, vaporized fuel is projected upstream from the jets 11A. Such an arrangement by itself has the defect that it surges if the pipes 11 are simply fed in parallel from a common source. It is obvious, for example, that slight inequalities of heat exchange as between the pipes of the vaporizer, can result in one tube starving of liquid fuel momentarily, whilst another gains. The starved pipe becomes hotter and the gaining pipe cooler, so the condition is self-aggravating, resulting in an unstable condition, cracking of fuel, and the building up of carbon in the pipes. Since one of the objects of the invention is to produce uniform distribution of heat in the delivered gases (as well as uniformity in a plurality of combustion chambers), the following means are adopted to overcome this difficulty.

The pipes 11 come from a common equalizing chamber 12, which is fed with liquid fuel under pressure by a fuel pipe 13, and which may contain a strainer such as a gauze 12A. Where each pipe 11 opens into the chamber 12, there is a small orifice 11B, which, conveniently, is a screwed-on nipple. The orifices of the nipples form restrictions, and they are selected so as to produce such pressure-drop across them, as will prevent surge in the vaporizers as a whole.

It is not possible readily to lay down any proportions or dimensions for the restriction orifices 11B; these depend on the nature, dimensions, running temperature, etc., of the pipes, the nature of the fuel, and the range of flow-rates to be used, and the character of the jet orifices at 11A.

The flame tubes 4 are perforated as at 4C for the admission of air from the casing 1. The air passing through these holes 4C, is regarded as "secondary" air, i. e. air not necessary to complete combustion. The "primary" air is that which passes through the baffle system. However, in practice it is found that with the high velocities and high rates of combustion for which the invention is intended to be used, the secondary air if properly admitted, speeds up combustion and shortens the flame. If it is admitted at too great a rate in one region, it may tend to quench the flame, which results in imperfect combustion or long flame. Various arrangements of holes can be devised, and again it is not possible to define usefully exactly what arrangement should be adopted, since it will depend on the conditions of use and the requirements to be met. In general, where the invention is to be used in the power unit previously referred to, the object is to raise the temperature of a large mass of high-velocity air uniformly, approximately six times as much air being passed through a combustion chamber as is necessary to burn the quantity of fuel used. The intimate and speedy mixture of the secondary air with the immediate products of combustion or flame, is therefore to be aimed at: experiment tends to show that good results are obtained if the ratio by mass (in unit time) of primary to secondary air is approximately as 2:4.

The procedure for lighting is; with a relatively low airflow the ignition is switched on and pilot jet turned on. The fuel from the pilot jet ignites and the ignition is switched off. The airflow may be slightly increased, and after a judged time, when the vaporizer pipes are well heated, the main fuel supply is turned on. The airflow is increased as soon as the fuel from the vaporizer burns, and thereafter the pilot jet is turned off. A wide range of fuel flow and corresponding airflow can now be covered, and providing the air:fuel ratio is kept substantially constant, uniform heating of the combustion products and remaining secondary air results.

Where the combustion chamber is one of a plurality, as shown in my aforesaid co-pending application Serial No. 379,734, the fuel manipulation is common to all, and ignition in one causes ignition in all, the flame stubs 4B communicating burning gases from one flame tube to its neighbors. One spark plug has been found to suffice for igniting a closed ring-like series of ten chambers.

The air stubs 1A balance the air pressures in the plurality of air casings.

The air casings 1 and the flame tubes 4, whether or not they be cylindrical as illustrated, are preferably always of circular cross-section if considerable pressures are to be dealt with and structural lightness is a consideration, as in aircraft power units of the type above-mentioned.

I claim:

1. In a combustion engine of the character described, means for burning liquid fuel comprising a plurality of circular-sectioned air casings adapted to be supplied in parallel with compressed air through openings adjacent one end

5

thereof, a circular-sectioned flame tube located coaxially within each of said air casings having one open end and additional openings in its side wall for the entry of air, the open end of each flame tube being that which is opposite the end of the associated air casing through which air is supplied to the latter, means for supplying fuel to said flame tubes uniformly adjacent the open ends of said tubes, means interconnecting the interiors of all of said air casings to balance the pressures therein, and means interconnecting the interiors of said flame tubes, said means interconnecting the air casings comprising air stub pipes extending between adjacent casings, and said means interconnecting the flame tubes comprising additional stub pipes of less diameter than and passing through said air stub pipes.

2. In a combustion engine of the character described, a plurality of combustion units each comprising a circular-sectioned air casing, means for delivering compressed air to the interior of

6

said casing, a circular-sectioned flame tube mounted coaxially within said casing and having one end open whereby compressed air from said casing enters and traverses said tube, means adjacent said open end for creating turbulence in the air entering said tube, means for supplying uniformly distributed fuel into the turbulent air within said tube, the wall of said tube being perforated at both axially and peripherally spaced points for the passage of secondary air thereinto from said casing, and an outlet conduit for conducting products of combustion from the other end of said flame tube to the exterior of said casing, means for interconnecting the air casings of said units, and means for interconnecting the flame tubes of said units, said interconnecting means comprising concentric pipes with the pipes connecting said flame tubes arranged within the pipes connecting said air casings.

FRANK WHITTLE.
